UNITED STATES PATENT OFFICE.

WILLIAM GOLDING, OF MOSS SIDE, COUNTY OF LANCASTER, ASSIGNOR TO
THE CLAVIGER CYCLE COMPANY, (LIMITED,) OF MANCHESTER, ENGLAND.

VELOCIPED.

SPECIFICATION forming part of Letters Patent No. 400,204, dated March 26, 1889.

Application filed July 14, 1887. Serial No. 244,340. (No model.) Patented in England October 9, 1885, No. 11,990, June 17, 1886, No. 8,049, July 16, 1886, No. 9,234, January 27, 1887, No. 1,304, and June 27, 1887, No. 9,091; in Belgium July 15, 1887, No. 78,050; in France October 27, 1887, No. 184,164, and in Germany April 21, 1888, No. 43,827.

To all whom it may concern:

Be it known that I, WILLIAM GOLDING, a subject of the Queen of England, residing at Moss Side, in the county of Lancaster, England, have invented certain new and useful Improvements in or relating to Velocipedes, (the same having been patented in the following countries, to wit: England, No. 11,990, October 9, 1885, No. 8,049, June 17, 1886, No. 9,234, July 16, 1886, No. 1,304, January 27, 1887, and No. 9,091, June 27, 1887; France, No. 184,164, October 27, 1887; Belgium, No. 78,050, July 15, 1887, and Germany, No. 43,827, April 21, 1888,) of which the following is a specification.

This invention relates, generally, to the application of a distinctive combination of rods or levers with movable fulera to the propulsion of and other functions in connection with velocipedes, such levers operating by a combination of direct thrust or pull and of leverage, and being designated "claviger" rods or levers.

It also relates to certain other details in the construction and steering and gearing up of velocipedes directly or indirectly arising from the employment of the said claviger rods or levers.

And in order that my said invention may be well understood, I now proceed to describe the same more particularly, and for that purpose refer to the accompanying sheets of drawings.

Figure 1 represents the driving mechanism for a bicycle with the driving-wheel in the rear, and Fig. 2 represents a similar movement applied to a tricycle. Figs. 3, 11, and 12 illustrate a modification of the driving-gear. Figs. 4 and 5 illustrate one variety of the roller-claviger. Fig. 6 shows a sun-and-planet gear for gearing up a bicycle. Figs. 7 and 8 illustrate another form of gearing. Fig. 9 is a view of an automatic steering device. Fig. 10 shows the preferred form of joint for claviger movements. Figs. 13 and 14 show the preferred form of a tricycle steering mechanism. Figs. 15, 16, and 17 show one form of sun-and-planet gear with the claviger-levers.

Fig. 18 represents a modification of Fig. 4. Figs. 19 and 21 show a modification of the 50 claviger-levers especially adapted to drive a tricycle through direct gears. Figs. 20 and 27 represent the claviger-rods adapted for driving tandems. Figs. 22, 23, and 24 are details. Figs. 25 and 26 show one form of 55 the claviger-levers with an improved steering-head.

The pedal-rod C C carries the pedal P at one end, and is pivoted at the other to a crank, b, either rigidly attached to the axle 6c of the wheel, or, when sun-and-planet gearing is used, it is pivoted to a crank or radius rod running loose on the axle, or to a crank fast on a spindle running loosely inside the hub. The pedal-rod C C is supported and 65 controlled by the link 11, which is pivoted at a point, S, above the pedal-rod to the framework. In order to allow room for the heel the pedal-rod is preferably curved downward, as shown, and the lower end of the link is 70 pivoted at x to the connecting-bracket d, which is rigidly fixed to the pedal-rod. The line of travel of the pedal-center for one complete movement is indicated by the dotted line. When the wheel is turned once 75 round for each double stroke, the up and down strokes are equal as to time. When the wheel is geared up by means of sun-and-planet gear-wheels, the downstroke takes 80 rather less time than the upstroke, the difference depending upon the length of the pedal-rod and the relative diameters of the planet-wheel and the sun-wheel. This arrangement, in combination with sun-and-planet gear in 85 the proportions shown in the figures, gives a mechanical advantage to the operator during the downward stroke, more particularly at the commencement of the stroke, where it is most required. The upward movement of the pedal is made correspondingly slower toward 90 the termination of the return-stroke. The relative times of the downward and upward strokes in the proportion shown are about as eleven to twelve.

Fig. 3 shows a modification, in which the 95 pedal-rod C C, while carrying the pedal P and

controlled by link 1 1, as before, is pivoted at the other end to a crank, *b*, which in this case is carried in bearings rigidly fixed to the frame-work or to the fork *B*. This is shown 5 on a larger scale in Figs. 11 and 12. The changeable spur-wheel *I*, rigidly connected with the crank-axle or crank, drives the pinion 2, which is fixed on the axle of the wheel 3. In this case the direction of travel of the 10 pedal indicated by the arrow is in the opposite direction from that of the pedal in Figs. 1 and 2. It will be understood that in this case the gearing, as well as the crank and pedal-rod, is duplicated on each side of the 15 machine.

Figs. 4 and 5 illustrate a variety of roller-claviger for operating the front wheel of a bicycle or tricycle. The pedal-rod *C C* is preferably made of steel tubing, bent as 20 shown, to accommodate the foot when the movement is at the lowest point. The circle marked *P* shows the pedal end. The pedal-rod is rigidly fixed at the other end to a cross-piece, *d d*, one end of which carries the stud 25 *S*, upon which the roller *r* turns. The other end of the cross-piece *d d* is pivoted upon the crank-pin *o* of the crank *b*. A *A* represent a continuation of the fork side, and form a bracket against which the roller *r* 30 bears during the movement. The roller *r* thus forms the movable fulcrum for the leverage part of the force. The slight guide *g* is to keep the roller in position. The roller is allowed a small amount of play between 35 the two surfaces.

Fig. 4 represents the movement applied to a tricycle with a single front driving-wheel and two small trailing-wheels. The mechanisms are duplicated upon the other side.

40 Fig. 6 represents a modification of the sun-and-planet gearing for gearing up velocipedes, the object of this modification being to effect the driving with a sun-and-planet wheel on one side only in combination with 45 the swinging claviger-rod, as before described. The drawings represent the parts in section. The hub of the wheel *h h* is hollow, its interior surface being cylindrical. A spindle, *s s*, passes through the hub, and is supported in- 50 side it preferably by balls *b b'* running between solid and hollow cones, the former adjustable by means of screw-threads and held in position by nuts and lock-nuts. The spindle and hub are concentric, and are free to 55 revolve on their axes independently of each other. A crank, *C C* and *C' C'*, is keyed or otherwise rigidly fixed to each end of the spindle. The cranks *C C'* at the crank-pin end are coned out to accommodate a coned pin, 60 *t t'*. The coned surfaces are preferably adapted for adjustable ball-bearings, as described, for the hub-spindle, but with one fixed cone, or they may be plain parallel bearings. In any case the crank-pin is allowed to freely 65 turn in the crank. The crank-pin after passing through the crank passes through the

pedal-rod *a a'*. The crank-pin is here made of greater diameter with flats and fitted into a slot of the same shape in the rod *a a'*. In this it is held firmly in position by the fixed 70 collar and nut shown; or the crank-pin may be fixed in the crank and the rod *a'* may be pivoted upon it in the usual way when gearing up is not required. When gearing up is required, the spur-wheel *r* is keyed or otherwise rigidly attached to the extended end of the hub *h*. Another spur-wheel, *p*, is keyed or otherwise rigidly attached to the end of the crank-pin *t'*, so as to gear with the spur-wheel *r*. The spur-wheel *p* is by this arrangement 75 prevented from turning upon its own axis, but is free to be revolved round the axis of the hub, carrying the spur-wheel *r* round with it and gearing up the driving-wheel. The grooves *d d'* represent the channels for the 80 balls for the bearings of the frame-work of the velocipede.

Figs. 7 and 8 show the application of my system of varying the number of revolutions by rolling contact. Fig. 8 shows the outlines 90 of the rollers and teeth with the geometrical curves for obtaining them. The proportions shown in the figure are for varying the revolutions in the ratio of three to four. Fig. 7 shows its application to the hub of a velocipede. The same letters refer to the same parts in each. The hub is formed of a hollow cylindrical drum, *h h*, preferably of gun-metal, which may be parallel or diminished in diameter in the middle, as shown, 95 having a projecting flange, *m m* and *m' m'*, along each edge, into which the spokes are screwed. Under one of the flanges this piece is recessed out for a short distance to admit the end piece, *k k*. This piece carries 100 an annular projecting boss, *j*, corresponding to boss *j'*, which is part of the drum *h*. Upon these bosses are fixed the bushes of the ball-bearing cases *a a* and *a' a'*, which are secured to the lower part of the fork sides *F F'*. The hub is free to turn inside these 105 bearings. The toothed wheel or curved flange *l l* is rigidly fixed to the inside of piece *k* and concentric with it. A spindle, *s*, having a crank at each end, is passed through the hub 110 and held in a position eccentric to it by the ball-bearing cases *b* and *b'*, attached to the end of the fork sides. The disk or wheel *n n*, carrying studs *p p*, upon which revolve the 115 rollers *r r*, is rigidly fixed to the spindle *s* in gear with the teeth *l l*. The spindle *s* is free to revolve without touching the hub when it actuates the hub, and consequently the driving-wheel revolves faster in the ratio of four to three. The gearing is effected by rolling 120 contact.

In Fig. 4 the application of this mechanism to a front-driving tricycle is represented in combination with the roller claviger-rod, as before described.

I would observe that I do not claim generally gearing up a velocipede inside the hub,

but only the novel and original method of effecting it by rolling contact inside the hub, as just described.

Fig. 9 represents a plan view, and in Fig. 4 is shown an elevation, of an arrangement for controlling the steering as adapted to a front-driving tricycle. A cam-shaped rod, C, is pivoted upon or rigidly fixed to the handle-bar *t t* at *a* and *a'*, on either side the head of which *h* represents the head-pin. A forked bracket, *e*, is pivoted through the forked ends to the backbone. At the upper end of this bracket a grooved roller, *d*, is pivoted. The roller is held firmly against the hollow in the cam by two springs, *p* and *p'*, which are each connected at one end to the ends of a stud, *s*, passing through the neck *n*, and at the other ends to a stud passing through the bracket *e*. When the steering wheel or wheels are turned from a straight course, the cam turns with them, and, pressing against the roller, forces it outward if the force operating is sufficient to stretch the springs. When the force ceases, the springs pull the wheels back straight again. It also holds the wheels straight against slight inequalities and renders the steering easier for the operator.

Fig. 4 also illustrates a combination of raked or inclined centers with a direct transverse handle-bar and steering-controller, substantially as last described, and I desire to state that I do not claim individually any of the points in this triple combination, but only their combination. The raked or inclined head carrying the centers is shown clearly at the top of fork A. *t* is the transverse handle-bar, and for the steering-controller (which, however, in this combination may be of any of the well-known suitable forms) I show the arrangement at *d e*, hereinbefore described and shown at Fig. 9.

Figs. 2, 13, and 14 show my novel steering arrangements as applied to tricycles with a single rear driving-wheel, and which are steered by the two front wheels. In these figures, *e* is the cross-bar connecting and carrying the two front steering-wheels. It is in advance of the center of the wheels, its ends being bent backward, as shown at *f*, and carrying the wheel-bearings at *g*. Rigidly attached to this cross-bar, and in the center of the machine, is the head or hinge *h* at a backward inclination of about one in four to the vertical. This head carries the centers, in which the neck-spindle *k* works, and this is rigidly attached to the main frame D. By this arrangement the main frame, with seat and rear driving-wheel, is caused to incline toward the center of the curve over which the tricycle is traveling, and the advanced position of the hinge relatively to the center of the steering-wheels gives a tendency for the said wheels to remain in a straight or central position when traveling. The handle-bar *m* and steering-pillar *n* are attached to the cross-bar *e* either rigidly—for a man's machine—or pivoted or hinged so that it can be turned

down or lowered away to the front, as shown at *o* in Fig. 2, to allow ample room for a lady to mount.

Fig. 10 shows my novel method of constructing joints or pivots for velocipedes actuated by levers, as herein described, B representing a bracket rigidly secured to the framework, and *c c* the pedal-rods. *dd* are brackets attached to the latter, and *11* are the controlling-links. These links are formed with bosses at each end, which fit in loosely between the bosses of brackets B and D. Centrally situated in the inner faces of each of these bosses are coincident hemispherical recesses, and into each spherical recess thus formed is inserted a hardened-steel sphere, as shown at *s*. For convenience of insertion, adjustment, and hardening of the recesses, I use screwed nipples or bushes *n*, instead of forming the recesses in the bosses of the brackets themselves. These nipples can be locked in position by lock-nuts or any convenient device. The recesses in the central boss of the double bracket B are formed in a plain piece, *r*, inserted therein for the purpose, and which may be secured in position by a pin, *p*. The oiling is effected by the holes *O*, as shown.

Figs. 11 and 12 show my method of changing and adjusting the gear-wheels so as to obtain different velocity ratios between the cranks and driving-wheels of velocipedes in which direct gearing is used, as represented in Fig. 3, and hereinbefore described. The pinion 2 is keyed or suitably fixed onto the axle of the driving-wheel and runs upon ball or other suitable bearings in the bracket *f*, which is secured at *f'* to the end of fork B, Fig. 3. A slot, *h*, is cut in this bracket, and the stud *i*, passing through it, is secured to the bracket by nut *W* and a collar. Upon this stud the crank *b* revolves, which carries upon its boss the spur-wheel *I*, prevented from turning on the boss by the screw *t*. *c* represents the end of the pedal-rod, and *v* the crank-pin, these being similar to those previously described. When it is desired to vary the gearing, the nut *W* and the screw *t* are removed. The crank *b*, stud *i*, and wheel *I* being then withdrawn from bracket *f*, the wheel can be removed and another one substituted, and on putting the parts together again the stud *i* is adjusted in the slot *h* to suit the radius of the newly-inserted wheel. These parts are duplicated upon the other side of the machine.

Figs. 15, 16, and 17 show a typical form and arrangement of claviger-lever and restraining-arm in connection with sun-and-planet gear for propelling velocipedes. A is a bracket attached at one end to the lower part of the fork side, and carrying at the other end the stud *S*, which is the fixed axis of the hanging claviger B C D S. The latter consists of a rod, B C D, and a link, C S, called the "restraining-arm." C is the pivot by which the two rods are attached to each other. By pref-

erence the restraining-arm SC is forked at C, and the pivot is formed in the method hereinafter described with reference to Fig. 10. Though the movement of these joints is very small the means described allow of adjustment for wear and prevent rattle. The rod B D carries the pedal P, which can be adjusted laterally and vertically by the screw e. The other end, at D, terminates in a boss, in which is cut a rectangular slot, as shown in Fig. 1. H is a small spur-pinion provided with a boss or projection on one side which fits into the slot in the end of the clavis-rod at D. K is a spur-wheel which is rigidly fixed to the axle of the driving-wheel. Between the spur-wheel K and the bearing-box P is a slotted radius-arm, N, which may be mounted loosely on a hardened-steel bush or sleeve attached to the spur-wheel K and to the axle of the driving-wheel. A spindle, n, having a fixed collar, is clamped in position in the slot of the radius-arm N by means of the nut n'. The spur-pinion H is mounted upon the spindle n, and is free to revolve upon it. The boss or projection of the spur-pinion H is passed through the slot in the end D of the clavis-rod B C D, and secured in position by the nut n''. The spur-pinion H is thus tied to the axle, and is held in gear with the spur-wheel K, while it is prevented from turning upon its own axis. The spur-pinion and wheel thus form the movement known as the "sun-and-planet gear." An alternative arrangement is to change the positions relatively of the radius-arm N and the spur pinion and wheel, the former being placed outside the latter. The rod B D may be bent laterally at G in order to narrow the tread. Fig. 17 represents them in position applied to a rear-driving tricycle. The spur wheel and pinion are completely covered in front the dust by a thin metallic box, x, which is supported inward round the boss of the radius-arm N and outward by the spindle n between the spur-pinion H and the clavis-rod D, and it revolves with these parts. It will be seen from the foregoing description that by loosening the nuts n', n'', and n''' the small spur-pinion or planet-wheel may be readily taken out and another with more or fewer teeth substituted, a supply of planet-wheels of different diameters being conveniently carried in the tool-bag.

Fig. 18 represents the form of claviger described as a roller-claviger of the second kind. A is a bracket attached to lower end of the fork side. It is recessed and bored to form a knuckle-joint for the ball-bearings, the box of which is shown at P'. The lower part of the bracket is extended forward, and is finished off below with a broader flat or grooved surface for the roller R to bear against. B C D is the clavis-rod or pedal-lever. It may terminate at the end B in a slotted are, as shown, to allow the pedal to be adjusted to different riders, or it may end with a boss to support a pedal which is not adjustable. In the latter case the clavis-rod D C B is straight in the

plane represented by the paper. It is bent laterally at G to allow of a narrower tread. The pivot at C is a long boss, giving a wide bearing on the crank-pin of the crank M, which is rigidly attached to the axle L of the driving-wheel. The end D is provided with a roller, R. The stress of the force both when the pedal is driving the crank and when the crank is returning the pedal into position is always upward against A'. The dotted lines and marks indicate the relative positions of the crank-pin and pedal-center at equal intervals of time during the movement. It will be seen that in this movement the variation of force is the same as in a pedal having rotary motion. The motion is peculiarly smooth and silent and free from vibration, as it has no fixed point. It is adapted to a bicycle having a large driving-wheel in front. The fork side is represented with a rake of one in four. This, together with the arrangement allowing the stroke to be given throughout in the rear of the axle, affords the necessary element of safety.

Fig. 19 represents a claviger-movement in combination with two spur-wheels in direct gear, adapted to propel a tricycle with two driving and steering wheels in front with a small rear trailing-wheel. The movement is a bent hanger-claviger of the first kind. The size and position of the driving-wheels in relation to the parts represented in the figure are indicated by the circle which represents them projected on the plane of the paper. The backbone, rear wheel, and seat are not shown. A is the front bone, consisting, as is usual, of a vertical hollow tube terminating at the upper end in the head. It is bent backward just above the axle and then continued vertically downward to S, as shown in the figure. Rigidly attached to it near the bend is the fork-piece A' and A'', depending from it to the right and left and then curved forward and downward. On the fork-pieces are the two bosses b, one on each side. Through each of these passes a vertical bolt carrying a knuckle-joint, Y, at the end, to which the ball-bearing box p is attached. L represents in cross-section the solid axle, and L' the hollow one, which are connected together by the balance-gear at one end. The ends of the forks each terminate in a knuckle-joint, V', which carry ball-bearing boxes p', which support at both ends a subsidiary axle, l. A crank, M, is keyed or otherwise securely attached at each end to this axle. On this subsidiary axle, between the two bearings, there is rigidly attached a spur-wheel, T. To the hollow axle L' there is likewise rigidly attached another spur-wheel, R, the centers being arranged so that the two are held in gear. The rod B C D is the clavis-rod or pedal-lever. S C is the restraining-arm, the fixed axis S being rigidly attached to the bottom of the tube A. The restraining-arm S C is pivoted to the clavis-rod at C. The end D terminates with a boss giving a deep bearing upon the

crank-pin. The crank-pin is adjustable in the usual way, allowing the length of stroke of the pedal P to be shortened or lengthened. In the figure the movement is represented at the commencement of the stroke. The dotted lines show the position of the movement on the other side of the machine at the termination of the stroke. The drawback to this class of tricycle has hitherto been the difficulty of steering and the danger of the brake, which, when put on under usual circumstances, causes the rear part of the machine with the rider to revolve round the driving-axle, much to the latter's discomfiture. The stroke of the foot being almost directly downward, the steering is rendered exceptionally easy. To remedy the latter drawback a safety brake and step combined are shown in the figure attached to the frame-work just described. The step *a c* is also the brake-lever with the fulcrum at *h* toward the lower end of the tube A. It is operated by the foot, which, when the machine is in motion, is withdrawn from a pedal for the purpose. The power is transmitted by the connecting-rod *i d* to the bell-crank lever *e*, which tightens a band-brake acting upon a drum rigidly attached to the hollow axle in the usual manner.

Fig. 20 represents a machine similar to the one just described, which may be operated by one or two riders—in the latter case forming a tricycle-tandem. The frame-work and tandem-movement will be first described. A straight vertical hollow tube placed behind the axle about the same distance as the lower part of the vertical tube shown in Fig. 19. The forked bracket, knuckle-joints, bearings, spur-wheels, cranks, and subsidiary axle are substantially the same as those shown in Fig. 19, and the same description will apply. The bracket D is rigidly attached to the upright tube A to support the adjustable seat-rod, spring, and seat with the supporting-handles, all of the usual kind. The movement is a double bent hanger-claviger of the first kind. The part E U C is preferably constructed in one piece. It terminates at E in a boss, which allows of a deep bearing on the crank-pin, which is adjustable, so as to allow the length of stroke to be varied. The other end terminates in a pivot at C, to which point the end of the restraining-arm C S is connected. The fixed axis is at S at the lower end of the front bone, A A. Just above the pivot C the rod E C has a strong boss, U, which is drilled or bored out to accommodate the rod B B'. The latter is by preference a hollow tube of steel. It carries at each end the two segmental slotted pieces *p* and *p'*, to allow of the adjustment of the pedals P and P' to suit different riders. The tube B B' can be moved backward and forward through the bearing in the boss U. Thus the length of the stroke can be adjusted between the two riders. If a lady occupies the front seat, the length U B' may be shortened and the

length U B correspondingly lengthened, the length of the stroke corresponding. When the rod B' U B is arranged in position, it is firmly held there by the set-screw *n''*. The rods then form a rigid cross. The movements of the two pedals are half a stroke apart. When one is at the commencement the other is at the middle of the stroke, so that full impulse without break is transmitted to the crank. The oscillation of the rod C S is in time between the other two, being a quarter of a stroke before one and a quarter of a stroke behind the other.

Fig. 21 represents a bent roller-claviger of the second kind applied to a tricycle with two rear driving-wheels and a smaller front steering-wheel. The fork-bracket, bearings, wheels, cranks, &c., are similar to those shown in connection with Fig. 19, and the same description will apply. The shape of the fork-bracket is different and the spur-wheels differently arranged to suit the altered conditions. A step, S, binds the two ends of the fork-bracket together and allows easy access to the saddle from the rear of the machine over the axle. The tube A of the upper end accommodates the seat-pin, which is adjustable as to height by means of the set-screw C.

Fig. 22 represents a longitudinal section of the steering-head or hinge of a velocipede. It is shown applied to a rear-driving bicycle in Fig. 17 and to a rear-driving tricycle in Fig. 21.

Fig. 23 represents the lower part of the head on a larger scale, so as more clearly to illustrate its details. In Fig. 22 the piece *b b' b'' b'''* represents the head and neck, which are tubular. They are preferably made in one piece, as shown, and the upper end of the neck *b'''* is brazed, by means of a cone-piece, into the rest of the backbone, which is connected with the axle of the rear wheel or wheels. The steering-rod *a a* passes through the head, having bearings within it for a short distance at each end at *b'* and *b''*. At its lower end it is rigidly connected to the washer *a''* and to the boss *a'*, which latter is securely brazed into the top of the fork of the small steering-wheel. The top and bottom of the head are made of greater diameter, so as to admit of an annular groove being cut into them to accommodate a ring of hardened-steel spheres, with which they are filled. Above and below the head are steel washers *C* and *C'*, bearing upon the steering-rod *a a* and free to move up and down upon it. They have an annular collar at the inside projecting slightly beyond the face of the washer in a direction away from the head. These steel washers have annular grooves cut into them opposite to and corresponding with the grooves cut into the head. The grooves and balls are fitted so that when brought together the faces of the head and of the washers shall not butt together, but that the head shall bear and roll upon the balls. Two steel washers, *e* and *e'*, are turned of the shape shown in the figures. They are thin disks with a thin

cylindrical center piece projecting on both sides of the disk. Round each of these washers two rubber rings are placed, one above and one below the disk. They are represented by r' , r'' , r''' , and r'''' . The fixed washer a'' has an annular projection or bearing similar to those on ball-bearing washers. The parts described are placed in position as shown in the figures. A loose steel washer 10 shaped the same as the fast one, a'' , is placed at the top reversed in position. A part of the steering-rod above the head is threaded and a nut, n' , placed upon it. This is slightly screwed down, the extent depending upon the weight of the rider. The lock-nut n is then utilized to hold all secure. The head of the machine is thus held in equilibrium between the rubber rings above and below, while the balls and channels are held together by an elastic tension. The rubber rings are held entirely by the washers e and e' , so that they cannot bind against the steering-rod or the other washers, but are free to be compressed or expanded in response to the 25 jolts of the small steering-wheel, the washers sliding upon each other inside and upon the steering-rod. In this manner the vibration of the front wheel is intercepted by the rubber. During steering the head rolls upon the balls 30 and renders the steering easier. The arrangement also prevents the rubber being injured by the erosive action of the oil as it is used.

Fig. 24 represents a detail of this improved head for velocipedes. Instead of the vertical spindle terminating in coned centers, which are very liable to break off and difficult to repair, they have a hemispherical hole cut at each end. The adjustable head-pin at the top 35 and the bush at the bottom of the spindle are treated in the same manner. Within these holes a rather large steel sphere is placed at top and bottom, and the spindle turns upon these spheres. When worn or broken they 40 can be readily replaced.

Fig. 25 represents a rear driving-tricycle of the form in which all the wheels operate in steering, combined with a suitable application of claviger driving and with an improved 45 form of anti-vibration springs. A A represent the main frame-work of the tricycle. It is L-shaped, and is composed of two straight pieces of steel tubing, one placed in a vertical and the other in a horizontal direction. These are joined together at the bend by a right-angled core-piece, which is pinned and brazed into both tubes. This core-piece carries two brackets, b'' —one on each side—and each bracket is widened out, and terminates 50 in a smooth plane surface about half an inch in width, set at an angle of forty-five degrees, or thereabout. These form the guides g for the rollers. Above the point of junction of the tubes a sleeve, i , carrying two forks, b' and b'' , is pinned and brazed round the tube. The upper forked bracket, b' , terminates in ball-bearing cases, which rest upon the hol-

low axle x' of the driving-wheels. The lower forked bracket also terminates in ball-bearing cases, which support a short subsidiary 70 shaft parallel to the main axle. This short shaft is carried through the bearings, and has a crank, d , securely fixed at each end one hundred and eighty degrees angular distance apart from each other. A spur-wheel, h , is keyed or otherwise rigidly fixed to the center of this short shaft, and it is arranged to gear with a spur-pinion, a , fixed upon the hollow axle, which is connected with the balance-gear of the driving-wheels. On 80 each side of the machine, pivoted to the cranks by the crank-pins, is a rod, B C D, carrying a roller, R, upon a fixed stud, C. The end B of the rod is slotted to accommodate a pedal, P, which is clamped in position in the usual 85 way. The upper end of the vertical tube accommodates a seat-rod which is adjusted vertically in it by means of a set-screw. The lower end of the tubular frame-work carries the neck j , with the steering-spindle p . The 90 head or steering centers are vertical and are placed midway between the axle x of the front wheel and the axle x' of the driving-wheels. They are held by lugs l and l' , which are securely attached toward the lower part of a 95 vertical tube, t' . The steering-rod with handle-bar of the usual bicycle pattern is placed within the vertical tube and is adjustable in it by means of a set-screw. The fork of the front wheel is placed horizontally and is connected to the head by two springs. The 100 springs are preferentially made of round bars of steel. Each one consists of a straight length with a single coil at the top and bottom. The ends of the bars are carried for a 105 short distance away from the coils in a direction parallel to the straight length and are then bent backward at right angles to it. The straight length of the spring is then secured to the end of the front wheel-fork by 110 bolts and screws, as shown in the figures. To effect this, a square-shaped rack-piece, w' , (see Fig. 26,) is firmly brazed to the nipple and end of the horizontally-placed fork w of the front wheel. This piece, when in position, has a smooth vertical face to the rear, 115 forming a hollow square. The upper and lower horizontal pieces of the square have each two concave recesses cut in them to accommodate the springs. The sides of the 120 springs opposite to these recesses are filed flat. The springs are then nipped in position by means of two shaped short flat steel rods, w'' and w''' , and four bolts and nuts, u u' and v v' , which pass through the pieces above 125 described. The two lugs l and l' , which support the steering-centers, are each made with a projecting boss on each side. These are drilled through in a horizontal direction, and the four ends of the two springs are passed 130 through these holes, each end through its corresponding hole, and the ends secured by set-screws. The two springs—the head and the front fork—are thus rigid together as far as

lateral movement is concerned, as neither spring can have any differential action apart from the other. The steering is therefore unaffected by the springs, but they are together 5 efficient for excluding the vibration of the front wheel from the rest of the machine.

Fig. 27 represents an application of the claviger system of driving to a tandem-bicycle. Direct spur-gearing is used, as in Fig.

10 3. The fork B is placed in an almost vertical position, and carries the bearings of wheels 1 and 2, as before. At its upper end it is attached to the backbone D, which is simply prolonged to the rear sufficiently to 15 carry the rear saddle, S', the front saddle, S, being carried in the usual way, as shown. k is the steering neck and spindle. The pedal P, the lever or pedal rod C, and restraining-arm l are very similar to those shown in Fig. 20 3, except that the lever C is rather longer to suit the altered position of the crank b. Rigidly attached to the lever C is an arm, d, carrying the rear pedal, P'. Both pedals are 25 adjustable in the ends of their lever-arms. t is the mounting-step for the front rider, and t' for the rear rider. The arrows show the direction of the pedals on their orbits.

Having now particularly described and ascertained the nature of my said invention, 30 and in what manner the same is to be performed, I declare that what I claim is—

1. In a bicycle or tricycle, the combination, with the pedal-lever having the pedal at one end and connected at the opposite end to the 35 crank connected by gearing to the axle of the driving-wheel, of the shifting fulcrum for said lever, located between the pedal and axle, substantially as described.

2. In a bicycle or tricycle, the combination, 40 with the pivoted pedal-lever having the pedal at one end and connected at the opposite end to the axle of the driving-wheel, of a shifting fulcrum, on which said lever pivots, consisting of the plane surface and the roller on the 45 lever, bearing theron, substantially as described.

3. In a bicycle or tricycle, the combination, with the drive-wheel and steering-wheel, the frame carried thereby, and pivoted pedal-lever 50 having the pedal at one end and connected to the drive-axle at the opposite end, of a shifting fulcrum, on which said lever pivots, formed by the plane surface carried by the lower rear portion of the frame, and a roller on the lever 55 for engaging said surface, substantially as described.

4. In a bicycle or tricycle, the combination, with the driving-wheel axle and the pivoted 60 pedal-lever connected thereto through intermediate gearing, of a shifting fulcrum, on which said lever pivots, located between the pedal and axle, and consisting of the plane surface carried by the frame, and the bearing on the lever engaging therewith.

65 5. In a bicycle or tricycle, the combination, with the driving-axle and the pedal-lever pivoting on a shifting fulcrum, of the sun-and-

planet gearing between said lever and axle, substantially as described.

6. In a bicycle or tricycle, the combination, 70 with the driving-wheel and pedal-lever pivoting on a shifting fulcrum, of the gear connected rigidly to the drive-wheel, and the gear engaging therewith connected rigidly to the pedal-lever, whereby a differential movement is given said parts, substantially as described.

7. In a rear-driving bicycle or tricycle, the combination, with the frame and driving-wheel, of the gear-wheel rigidly connected to 80 the driving-wheel, the gear-wheel carried by the frame, the forwardly-extending pedal-lever connected to said last-mentioned gear and having the pedal at its forward end, and the shifting fulcrum between said pedal and gear-wheel, substantially as described.

8. In a bicycle or tricycle, the combination, with the sun-and-planet driving-gearing and the pedal-lever pivoting on a shifting fulcrum rigidly connected to the planet-gear, of the 90 axle passing through the center of the sun-gear, the pedal-lever connected to said axle, and the crank connecting the axle and planet-gear, substantially as described.

9. In a bicycle or tricycle, the combination, 95 with the sun-wheel rigidly secured to the drive-wheel, of the planet-wheel mounted in slots in its supporting-arm, whereby different-sized gears may be employed and the pedal-lever connected to said planet-wheel.

100 10. In a bicycle or tricycle, the combination, with the driving-wheel having the gear-wheel connected rigidly thereto, and the loose axle passing through the center of the driving-wheel, of the gear-wheel carried by said 105 axle and engaging the gear-wheel on the driving-wheel, the crank on said axle, and the pedal-levers pivoting on a shifting fulcrum and connected to said axle, substantially as described.

110 11. The combination, in a tricycle having the front steering-wheels and axle, and the rearwardly-extending frame and drive-wheel, of the bearing for the neck on the rearwardly-extending frame mounted below the steering-wheel's axle forward of the center of such wheels and inclined from the top backward, whereby the drive-wheel and frame are tilted in turning, substantially as described.

115 12. In a tricycle, the combination, with the two front steering-wheels and the rear driver, of the arched axle for the steering-wheels having the bearing for the drive-wheel frame below the same and inclined from the top backward, substantially as described.

125 13. In a tricycle, the combination, with the two front steering-wheels and the rear driver, of the forwardly-inclined arched axle for the steering-wheels having the bearing for the drive-wheel frame below the same and inclined from the top backward, substantially as described.

130 14. In a tricycle or bicycle, the combination, with the drive-axle and crank, of the pivoted

pedal-lever connected to said crank and having a pedal-extension and pedal on each side of its pivotal point, whereby two riders may drive with a single lever, substantially as described.

15. In a bicycle or tricycle, the combination, with the drive-axle and the pedal-lever pivoting on a shifting fulcrum and connected with said axle, of the pedal-extension and pedal on each side of the pivotal point of said lever, substantially as described.

16. In a bicycle or triycle, the combination, with the drive-wheels, the pedal-lever pivoting on a shifting fulcrum, and intermediate gearing connecting the same, of the pedal-extension and pedal on each side of the pivotal point of said lever, substantially as described.

17. In a bicycle or tricycle, the combination, with the drive-wheels, the pedal-lever pivoting on a shifting fulcrum, and intermediate gearing connecting the lever and drive-wheel, of the pedal-extension and pedal on each side of the pivotal point of said lever, substantially as described.

25. 18. The combination, with the drive-axle and the pivoted pedal-lever connected there-

with, of the curved slot in the end of said lever and the pedal mounted therein, substantially as described.

19. The combination, with the pivoted pedal-lever, of a bearing therefor formed of the concavities on each side of the same, the adjustable screws having concavities therein, and the single ball fitting in said concavities, substantially as described.

20. The combination, with the tubular head and the steering-bar passing through the same, of the rubber buffers at top and bottom carried by the washers, having flanges for preventing contact of the rubber with the steering-bar, substantially as described.

21. The combination, with the steering-head of a triycle, of the steering-wheel and frame, and the top and bottom coil-springs connecting the said head and steering-frame, substantially as described.

In testimony whereof I have hereunto set my hand in the presence of the two subscribing witnesses.

WILLIAM GOLDING.
